(57) **CLAIM**

The ornamental design for an electronic gaming cabin, as shown and described.

DESCRIPTION

FIG. 1 is a top, front and right side perspective view of an electronic gaming cabin, showing our new design;

FIG. 2 is a top, rear and right side perspective view thereof; FIG. 3 is a bottom, front and left side perspective view thereof;

FIG. 4 is a bottom, rear and left side perspective view thereof;

FIG. 5 is a front elevation view thereof;

FIG. 6 is a rear elevation view thereof;

FIG. 7 is a left side elevation view thereof;

FIG. 8 is a right side elevation view thereof;

FIG. 9 is a top plan view thereof; and,

FIG. 10 is a bottom plan view thereof.

The dashed broken lines depict portions of the electronic gaming cabin in which the design is embodied that form no part of the claimed design.
